UNITED STATES PATENT OFFICE.

FRED N. LA CHAPELLE, OF BEVERLY, MASSACHUSETTS, ASSIGNOR TO UNITED SHOE MACHINERY COMPANY, OF PATERSON, NEW JERSEY, A CORPORATION OF NEW JERSEY.

THREAD-HANDLING MACHINE.

1,185,108.

Specification of Letters Patent.

Patented May 30, 1916.

Application filed March 31, 1913. Serial No. 757,926.

To all whom it may concern:

Be it known that I, FRED N. LA CHAPELLE, a citizen of the United States, residing at Beverly, in the county of Essex and State of Massachusetts, have invented certain new and useful Improvements in Thread-Handling Machines; and I do hereby declare the following to be a full, clear, and exact description of the invention, such as will enable others skilled in the art to which it appertains to make and use the same.

The present invention relates to thread handling machines and more particularly to machines of this type which are employed for temporarily fastening the upper and sole of a lasted shoe together, preliminary to the permanent sewing of the inseam.

In order to expedite the shoe making operation and improve the quality of the finished product it is desirable to remove all of the temporary metallic fasteners prior to the sewing of the inseam and retain the upper and sole in lasted position by thread fastenings. The thread fastenings may be inserted before the metallic fasteners are removed from the shoe and do not interfere in any manner either with these fasteners or with the subsequent operations taking place upon the shoe.

The object of the present invention is to provide a machine of a simple and compact construction for inserting individual unconnected thread fasteners through the upper and lip of the insole to retain the upper in its lasted position during the uniting of the upper, welt, and insole by a seam of connected thread stitches.

With this object in view, one feature of the invention consists in the combination of work positioning devices, thread fastener forming and inserting devices, and thread cutting devices, co-operating during each cycle of operations of the machine to form and insert a thread fastener through the upper and insole lip of a lasted shoe and sever a length of thread from the supply.

In the preferred form of the invention, mechanism is provided for forming and inserting a thread fastener through the upper and lip of the insole and for automatically severing the supply thread at the completion of the fastener.

In order to allow the removal of all of the temporary metallic fasteners from the shoe, the toe wire and anchor tacks are replaced

by a thread passed about the toe and anchored at its opposite ends by thread fasteners.

With this end in view, a further feature of the invention consists in thread fastener forming and inserting devices and thread cutting devices, co-operating during each cycle of operations of the machine to form and insert a thread fastener through the upper and insole lip of a lasted shoe and sever a length of thread from the supply, and means under the control of the operator for rendering the cutting devices inoperative to permit two thread fasteners to be connected by a length of thread.

A further feature of the invention consists in the combination of work positioning devices for causing a thread fastener to be inserted through the upper and lip of the insole, and mechanism for imparting a plurality of advancing movements to the needle and a feeding movement between each two advancing movements to shift the path of the advancing movement in each case.

A still further feature of the invention consists in the combination of work positioning devices, and mechanism for automatically passing two loops of thread through the work from the same side, passing one loop of thread through the other upon the opposite side of the work, and pulling upon the thread from the first side to lock the fastening in the work.

Still further features of the invention consist in certain novel features of construction, combinations and arrangements of parts hereinafter described and claimed, the advantages of which will be obvious to those skilled in the art from the following description.

In the accompanying drawings:—Figure 1 represents a front elevation of a machine embodying the several features of the invention in their preferred forms; Fig. 2 is a right-hand side elevation of the machine shown in Fig. 1; Fig. 3 is a left-hand side elevation of the machine shown in Fig. 1; Fig. 4 is a detail illustrating a plan view of the work positioning devices, and mechanism for cutting the thread; Fig. 5 is a detail illustrating a side elevation of the mechanism shown in Fig. 4; Fig. 6 is a detail illustrating a plan view of the mechanism for locking the back gage in operative position and for rendering the thread cutting

means inoperative; Fig. 7 is a detail illustrating a side elevation of the mechanism shown in Fig. 6; Fig. 8 is a detail illustrating the thread clamp and tension, and adjustment therefor; Fig. 9 is a detail illustrating a front elevation partly in section, of the needle, channel guide, and thread carrying finger; Fig. 10 is a detail illustrating a side elevation partly in section, of the work positioning devices and needle, and showing the manner in which the needle passes through the upper and lip of the insole to form a thread fastening; Fig. 11 is a detail showing a longitudinal section of the curved eye needle; Figs. 12 to 20 inclusive are detail views illustrating somewhat diagrammatically the successive steps in the formation of a stitch; and Fig. 21 illustrates a longitudinal section in plan, of the toe of a lasted shoe, showing the location and form of the thread fastenings and the manner in which the thread is passed about the toe to replace the toe wire.

In the present invention, a plurality of thread fastenings are inserted through the upper and lip of the insole of a lasted shoe to retain the upper in its lasted position during the sewing operation and allow the removal of all of the metallic fasteners. As the location of the thread fastenings is wholly under the control of the operator, they may be inserted between the tacks at approximately the points of greatest strain, avoiding any liability of breaking a needle by contact with the lasting tacks. In the simplest and most efficient form of the invention which has yet been devised, the thread fastening is made by passing two loops of thread successively through the upper and lip of the insole from one side, passing the first loop through the second upon the opposite side of the work, and finally pulling upon the supply thread from the first side to draw the second loop into the work and lock the stitch.

The machine shown in the illustrated embodiment of the invention is provided with a curved eye needle 3 which is actuated to pass successive loops of thread 4 and 5 through the layers of material, as shown clearly in Figs. 12-20, inclusive. After the first loop 4 of thread has been passed through the work it is engaged upon the opposite side of the work by a hooked thread finger 6 which holds the loop during the retracting movement of the needle, and which is actuated to pass the first loop of thread through the second at the proper time. After the first loop has been passed through the second the needle is retracted and a pull is exerted upon the supply end of the thread from the first side of the work to draw the loop 5 into the work and lock the stitch. In order to clamp the short end of the thread, as shown in Figs. 13 to 15 inclusive, and pre-

vent its being drawn through the work, the under side of the needle is provided with a groove 8 in which the supply side of the loop lies and is allowed to slide freely. When the needle advances, the short end of the thread is clamped between the needle and work and all of the thread for the formation of the loop is drawn from the supply side, the advancing movement of the needle being accurately gaged to position the upper side of the loop opposite the end of the thread finger. The needle 3 is clamped in the usual manner to a needle segment 10 fulcrumed at 13, and oscillated to impart the proper movements to the needle by a bell crank lever 15 journaled upon a shaft 16. In order to lengthen the throw which is communicated to the needle segment by the bell crank 15, one arm 17 of the bell crank is provided with a lever 18 pivoted centrally upon the end of the arm and connected at one end to the upper portion of the needle segment through a link 19. The opposite end of the lever 18 is provided with a longitudinal bore which slidably supports a pin 20, secured in a T shaped member 21 journaled in a head 26 to be described. With this construction when the bell crank lever 15 is rocked in one direction a longer rocking movement in the opposite direction is imparted to the needle segment through the lever 18 and link 19. The proper movements are imparted automatically to the bell crank 15 by a cam 29 secured to a cam shaft 22 and having a face cam 23 formed upon one side thereof, and engaging with a cam roll 24 journaled upon the arm 25 of the bell crank. In addition to passing two loops of thread successively through the work, a feeding movement is imparted to the needle between the advancing movements to cause the path of the advancing movement of the needle in each case to be shifted.

In the present construction a linear feeding movement is imparted to the needle to cause the advancing movement of the needle to pierce the work at a plurality of points located in spaced relation to one another. To this end the needle segment is supported upon a head 26 which is slidably mounted upon parallel guide bars 27 and 28 rigidly secured in the machine frame. The proper feeding movements are automatically imparted to the head 26 by a cam 30 provided with a peripheral cam path 31 engaged by a cam roll 32 journaled upon a laterally extending stud 33 secured in the head. In order to maintain the connections for operating the needle segment intact when a feeding movement is imparted to the needle, the T shaped member 21 is journaled in bearings formed upon the head 26, and the lever 18 is loosely journaled upon a laterally projecting stud 32 secured in the arm 17 of the bell crank. The lever 18 is permitted to rock

and to slide freely upon the stud 32 which is of sufficient length to allow the necessary feeding movements of the needle segment to be communicated through the lever 18. The 5 thread finger 6 engages the first loop of thread and holds it during the retraction of the needle and the formation of the second loop after which the finger is actuated to pass the first loop through the second and 10 hold both loops during the retracting movement of the needle. As will be noted from an inspection of the drawings, the finger is provided with a hook 34 formed upon one side, which engages the first loop and carries it through the second in such a manner 15 that when the needle is retracted the second time the second loop binds upon the first and prevents the withdrawal of the loop with the finger. The finger 6 is supported 20 upon a finger carrying slide 35 which is slidably mounted upon the parallel guides 28 and 36 and is actuated to impart linear movements to the finger by a cam 38 secured to the cam shaft 22 and provided with a 25 peripheral cam path 39. The cam 38 is connected to the slide 35 through a cam roll 40 journaled upon a laterally projecting stud 41 secured in the slide and engaging with the cam path 39. In order to properly engage 30 the first loop and pass it through the second, the thread finger is arranged to pass over and in close proximity to the curved shank of the needle and with this arrangement, if a slight upward springing of the 35 needle occurs when passing either loop through the work, the thread finger will not exercise its proper functions. To avoid this, the thread finger is slidably mounted in the slide 35 and is yieldingly held in operative 40 position by a spring 42 and a collar 37 secured to the finger and cooperating with the slide to limit the downward movement of the finger which is normally positioned with its lower end as shown in Fig. 9. In 45 this position the finger normally passes over the top of the needle shank, but if a slight upward springing of the needle occurs to cause the finger to contact with the shank, the spring 42 yields and allows the finger to ride over 50 the top of the needle. As the thread finger moves in a linear direction it is desirable to raise the upper side of the loop 5 in order that the thread finger shall pass between the side of the loop and the shank of the needle. 55 This is conveniently accomplished by increasing the forward throw of the needle when passing the second loop of thread through the work, and to this end the face cam 23, as will be clear from an inspection 60 of Fig. 2 of the drawings, is designed to impart two forward throws of varying degree to the needle.

The work is positioned to cause each thread fastening to be inserted through the upper and lip of the insole by a channel

guide 43 engaging with the inside of the lip of the insole, and a back gage 45 engaging with the outside of the upper opposite the channel guide. In order to rigidly hold the channel guide in fixed position and 70 avoid interference with the shoe which is being operated upon, the channel guide 43 is adjustably secured to the free end of a lateral depending arm 47 which is clamped to the guides 27 and 28 by clamping nuts 75 78 48. The channel guide is provided upon opposite sides with two projecting feet 50, which serve to support the work in close proximity to the points at which it is pierced by the needle. 80

From an inspection of Fig. 9 it will be noted that when passing the first loop of thread through the work the needle passes just inside of one of the feet and that when passing the second loop of thread through 85 the work the needle passes just inside of the opposite foot. In order to accommodate varying thicknesses of work the back gage 45 is yieldingly moved into operative position, clamping the work against the channel 90 guide 43. The back gage 45 is secured to the front end of a back gage carrier 53 which is supported at its opposite ends by parallel links 56 and 57, pivoted to the machine frame at 58 and 59 respectively. The carrier is yieldingly advanced into an operative position by a tension spring 61 connected at its opposite ends to studs 62 and 63 mounted upon the machine frame and the carrier 53, respectively. After the back 100 gage has been yieldingly advanced into an operative position to press the work against the channel guide it is locked to positively clamp the work during the formation of the thread fastening. The link 57 supporting 105 one end of the back gage carrier is provided with a laterally extending arm 74 which has a ratchet tooth segment 75 formed thereon and oscillating with the link 57 when the back gage carrier is advanced or retracted. The segment 75 is positively locked when the back gage carrier is advanced by a pawl 76 which is secured upon the lower end of 110 a pawl carrying lever 77. The lever 77 is pivoted between its ends upon a shaft 69 secured in upstanding arms 70, and is actuated at the proper intervals by a cam path 78 engaged by a roll 79, journaled upon the upper end of the back gage carrier, as shown in dotted lines in Fig. 3 of the 115 drawings. In order to provide a yielding engagement of the pawl 76 with the ratchet segment 75 the pawl is rigidly secured to the lower end of an arm 80 pivotally supported at 81 upon the lever 77 and provided with an upstanding projection 82 which is connected with the lever 77 by a tension spring 83. At the completion of the thread fastening operation it is desired to release the 120 work and accordingly mechanism is pro- 125 130

vided for automatically moving the back gage away from the channel guide and for retaining it in this position until the machine is again started to allow the work to be readily removed from and inserted in the machine. To this end, the rear end of the carrier is provided with an L shaped member 65 which is engaged by a roll 66 journaled upon the lower end of a back gage lever 67 pivoted between its ends upon the shaft 69. The back gage lever is rocked automatically at the proper intervals by a face cam formed upon one side of the cam 21 and engaged by a cam roll 72 journaled upon the upper end of the back gage lever.

After both loops of thread have been passed through the work and the first loop of thread has been passed through the second, a pull is exerted upon the supply end 20 of the thread to draw both loops into the work and lock the stitch. The thread before passing through the eye of the needle is carried over a roll 85 journaled in the free end of a take-up lever 86. The take-up 25 lever is fulcrumed at its opposite end upon the shaft 69 and is actuated from a cam path 88, shown in dotted lines in Fig. 2, and engaged by a roll 89 journaled upon the lever between its ends.

During the operation of the take-up lever 30 the end of the supply thread is locked to prevent more thread being drawn from the supply by a thread clamp 92 which binds the thread to the grooved periphery of a roll 35 90 supported upon an arm 91. The thread clamp 92 is formed upon one arm of a bell crank lever pivotally supported upon the machine frame at 93 and having a roll 94 journaled upon its opposite arm and engaging 40 with a cam path 95 formed upon the periphery of the cam 29. The roll is retained in engagement with the periphery of the cam 29 by a tension spring 96 connected to one arm of the bell crank. In order to vary 45 the clamping effect of the thread clamp 92 it is provided with an adjusting screw 98 which bears against a stud 99 upon which the roll 90 is journaled and limits the movement of the thread clamp in the direction of 50 the roll 90.

In order to completely fill the holes in the work and lock the fastening tightly, a waxed thread is conveniently employed, and to this end, the thread is led from any convenient type of wax pot (not shown) over a guide roll 100, journaled in a bracket 101 secured to the rear portion of the machine frame and from the guide roll 100 to the thread clamp 92.

It is desirable to put some tension upon the thread when passing about the toe in order that the upper shall be held tightly by the thread, and for this purpose the thread clamp is conveniently utilized as a 65 tension device. The peripheral cam 95 is

provided with two recessed portions 103 and 104 which allow the thread clamp under the action of the spring 96 to lock the thread during the action of the take-up, and to put a suitable tension upon the thread 70 when passing about the toe. In the illustrated embodiment of the invention the locking movement of the thread clamp is determined in each case by the position of the adjusting screw 98, and this movement is 75 sufficient to act as a thread clamp to set the stitch in the work when the take-up acts and put a suitable tension on the thread when passing about the toe.

It will be obvious to those skilled in the art that the pressure of the thread clamp may be sufficient to lock the thread when setting the stitch and yet allow the thread to be drawn under tension from the supply when passing about the toe.

In order to increase the efficiency of the thread fastening operation it is desirable to use as little thread as possible and to secure the shoe in such a manner that the thread fastenings will not interfere in the slightest degree with the inseam sewing operation. To this end, after the thread fastening has been completed and the lock set in the work the supply thread is automatically cut close to the work and the shoe is then fed manually to form the next fastening. In this manner only sufficient thread is employed to make each fastening and the individual fastenings are not connected by loose lengths of thread to show above the welt in the completed shoe and become entangled with the line of inseam stitches, preventing the ready removal of the welt, if so desired. In the illustrated embodiment of the invention a thread cutting knife 110 is pivotally supported upon the back gage and is provided with a cutting edge 111 arranged to shear the thread against one edge of a rectangular slot 112 through which the thread passes. The thread cutter 110 is secured in an arm 115 of a bell crank lever pivotally supported upon the back gage at 116 and having its opposite arm 114 connected to the back gage carrier through a tension spring 117. The movement of the bell crank to carry the knife into an inoperative position is limited 115 by a stop 118 formed upon the back gage and bearing against the rear face of the arm 114. From an inspection of Figs. 4 and 5 of the drawings it will be observed that the coöperating shearing faces of the knife and back gage are positioned at an angle to the plane of movement of the knife, thus the thrust of the knife due to the shearing of the thread is in a plane approximately normal to the axis, and as there is no considerable force tending to force the knife in a vertical direction away from the back gage, a comparatively thin, light knife may be 120 employed. A positive cutting stroke is im-

parted to the knife by the slide rod 120 which is supported in bearings formed in the machine frame and has its front end engaging with the arm 114 of the bell crank. 5 The slide rod 120 has the proper movements imparted to it by a cutter actuating lever 121 pivotally supported upon the shaft 69 and having one end connected to the slide rod and its opposite end operatively connected 10 through a cam roll 122 with a peripheral cam 123, shown in dotted lines in Fig. 3. The cam roll 122 is retained in engagement with the cam 123 by a spring 124 secured at one end to the shaft 69, and positioned 15 with its opposite end bearing against the rear face of the lever 121. With this construction, a rapid cutting stroke is positively imparted to the knife 110, at the completion of which the slide rod 120 is moved out of 20 engagement with the bell crank, which is then oscillated by the spring 117 to move the cutter into an inoperative position. In order to vary the movements of the slide rod 120, and the operative movement of the 25 thread cutter, the lower end of the lever 121 loosely receives the threaded end of the slide rod 120 which is retained from longitudinal movement relative to the lever by a pair of clamp nuts 125 and 126. By adjusting the clamp nuts on the slide rod the position of the rod relative to the thread cutter may be varied as desired, thus varying the 30 time and extent of the shearing stroke of the cutter. It will be noted that the backward movement of the slide rod is sufficient to prevent interference of the slide rod and bell crank when the back gage is retracted to release the shoe.

40 In order to pass a thread about the toe of the shoe it is desirable that mechanism under the control of the operator be provided to throw the cutting mechanism out of operation and allow a thread fastening to be inserted, the loose thread passed about 45 the toe, and a second thread fastening inserted upon the opposite side of the shoe to anchor the toe thread in position. The slide rod 120 is provided with an inclined end portion 127 normally lying in a horizontal plane to position the end of the rod in line with the arm 114 of the bell crank lever. The slide rod is rendered inoperative by partially rotating it into a position 50 where the bent end extends downwardly, thus causing it to clear the bell crank when the slide rod is moved in the direction of its length. A toothed segment 130 is secured to the slide rod and meshes with a vertical rack 131 secured to the upper end of a treadle rod 132. The treadle connections are such that the bent end of the slide rod is normally retained in alignment with the bell crank lever, but upon depressing the treadle the slide rod 55 is partially rotated to turn this end down-

wardly and render the cutting mechanism inoperative.

In the present invention, the machine is automatically stopped at the completion of the predetermined cycle of operations and in the illustrated embodiment of the invention this is accomplished in a single revolution of the cam shaft. The cam shaft is rotated by a drive pulley 135 loosely journaled upon the shaft and provided with a conical clutch face arranged to engage at predetermined intervals with a co-operating clutch face formed upon a spider 137 secured to the shaft. The two clutch faces are held in engagement with one another during one complete revolution of the cam shaft by any suitable form of one revolution clutch which is arranged to positively stop the rotation of the cam shaft upon releasing the clutch. The clutch is controlled by a sliding trip member 138 operatively connected with the treadle through a treadle rod 140 and slide 141. After the slide 138 has been depressed sufficiently to allow the clutch to engage and start the machine it is automatically disengaged from the treadle and allowed to return to its normal position independently of the position of the treadle. To this end the slide 141 is provided with a hook shaped upper end 142 engaging with a co-operating hook 143 formed upon the member 138. The slide and trip member are disengaged by a stationary cam member 145 secured to the machine frame and co-operating with an inclined face formed upon the slide 141 to move the slide to the right, as shown in Fig. 3, and disengage the two hooks. The member 138 and slide 141 are independently returned to their normal positions by tension springs 146 and 147 connected respectively to the two.

55 The mode of operation of the machine is as follows:—The lasted shoe is first manipulated by the operator to position the channel guide against the inside of the lip of the insole at a point where the insertion of the tread fastener will not interfere with any of the metallic fasteners in the shoe. The machine is then started, causing the back gage to be yieldingly advanced into an operative position in which it is locked, clamping the shoe firmly during the formation of the stitch and pressing the upper and lip of the insole together to cause the thread fastening to hold them tightly, as shown clearly in Fig. 10. The needle is then advanced to pass the first loop of thread through the upper and lip of the insole from the outside of the shoe, and the loop is engaged and held during the retracting movement of the needle by the hook shaped end of the thread finger. The needle is then withdrawn from the work and the needle carrying slide is actuated to impart 100

- 8
- a feeding movement to the needle and locate it in position for the next advancing movement. The needle is again advanced to pass a second loop of thread through the work, this second advancing movement being greater than the first to allow the thread finger to carry the first loop between the upper side of the second loop and the shank of the needle. After the thread finger has completed the passing of one loop through the other, the needle is retracted, binding the second loop upon the first and holding the first loop in position during the withdrawal of the thread finger. The needle then continues its retracting movement until completely withdrawn from the work and during this movement the take-up is actuated to pull the second loop into the work and lock the stitch.
- 20 From an inspection of the drawings, it will be noted that the needle has a fixed throw to always pass each loop of thread through the work a predetermined distance with relation to the channel guide. During the feeding movements of the needle, the proper amount of thread is drawn from the supply and as the inside of the lip upon which the loops are formed is always positioned in the same relation to the movement of the needle, the loops will always be passed through the same distance and the thread supply will automatically give up varying amounts of thread, depending upon the thickness of the work. In a like manner, as the take-up lever has a predetermined movement imparted thereto, the thread lock is always drawn into the work the same distance, regardless of the thickness of the work and without necessitating any automatic measuring instrument or other device which is regulated for the thickness of the work. Upon the completion of the fastening the thread cutter is actuated to shear the supply thread close to the surface of the upper and the back gage is then retracted to release the shoe. Upon the completion of the predetermined cycle of operations, the machine is automatically stopped and it will be observed from an inspection of the drawings that this complete cycle is performed in one revolution of the cam shaft, thus enabling the operation of the machine to be controlled with a simple and compact mechanism. In order to retain the toe portion of the upper in place, a fastener is inserted at one side of the toe and before the cutting mechanism is set into operation the treadle is depressed to render this mechanism inoperative. The cycle of operations, with this exception, is performed in the usual manner and when the fastener is completed the shoe is turned to pass the supply thread about the toe, the tension device enabling the thread to be bound tightly against the upper. After the thread has been passed
- completely about the toe the shoe is again positioned in the machine and a second fastener inserted on the opposite side of the toe, the two fasteners anchoring the toe thread tightly in place to retain the toe of the upper in its lasted position. It will be noted that this operation of applying the toe thread is readily accomplished because of the fact that the supply thread is drawn from the outside of the shoe and when a fastener is completed the supply thread is in convenient position either to be served or utilized as a toe binder.
- While it is preferred to employ the specific construction and arrangement of parts shown and described, it will be understood that this construction and arrangement is not essential except so far as specified in the claims, and may be changed or modified without departing from the broader features of the invention.
- The invention having been described, what is claimed is:—
1. A machine for inserting individual unconnected thread fasteners through the upper and insole lip of a lasted shoe, having, in combination, a back gage, a channel guide, thread fastener forming and inserting devices, and thread cutting devices, coöperating during each cycle of operations of the machine to form and insert a thread fastener through the upper and insole lip of a lasted shoe and sever a length of thread from the supply.
  2. A machine for inserting individual unconnected thread fasteners through the upper and insole lip of a lasted shoe, having, in combination, work positioning devices, thread fastener forming and inserting devices, thread cutting devices, coöperating during each cycle of operations of the machine to form and insert a thread fastener through the upper and insole lip of a lasted shoe and sever a length of thread from the supply, and means under the control of the operator for rendering the cutting devices inoperative to permit two thread fasteners to be connected by a length of thread.
  3. A machine for inserting individual unconnected thread fasteners through the upper and insole lip of a lasted shoe, having, in combination, a channel guide, a back gage, thread fastener forming and inserting devices, thread cutting devices, coöperating during each cycle of operations of the machine to form and insert a thread fastener through the upper and insole lip of a lasted shoe and sever a length of thread from the supply, and means for automatically stopping the machine at the completion of the predetermined cycle of operations.
  4. A thread handling machine, having in combination, work positioning devices, mechanism for passing two loops of thread through the work from the same side and

passing one loop of thread through the other upon the opposite side of the work, means for releasing the encircled loop, and means for pulling upon the thread from the first side to thereafter draw the loops into the work and lock the fastening.

5. A thread handling machine having in combination, work positioning devices, mechanism for passing two loops of thread successively through the work from the same side, passing the first loop of thread through the second upon the opposite side of the work, means for releasing the encircled loop, and means for pulling upon the supply thread from the first side to thereafter draw the second loop into the work and lock the stitch.

6. A machine for inserting individual unconnected thread fasteners through the upper and insole lip of a lasted shoe having, in combination, a needle, mechanism for imparting a plurality of advancing movements to the needle and a feeding movement between each two advancing movements to shift the path of each advancing movement, and work positioning devices to cause the fastening to be inserted through the upper and lip of the insole.

7. A machine for inserting individual unconnected thread fasteners through the upper and insole lip of a lasted shoe having, in combination, a needle, a needle carrying slide, mechanism for imparting a plurality of advancing movements to the needle in different paths and for actuating the needle carrying slide to feed the needle between the advancing movements to shift the path of the advancing movement, and work positioning devices for causing the fastening to be inserted through the upper and lip of the insole.

8. A machine for inserting individual unconnected thread fasteners through the upper and insole lip of a lasted shoe having, in combination, mechanism for forming a thread fastening, a back gage and channel guide for causing the fastening to be inserted through the upper and lip of the insole, and mechanism for automatically severing the supply thread upon the completion of the fastening.

9. A machine for inserting individual unconnected thread fasteners through the upper and insole lip of a lasted shoe having, in combination, mechanism for forming a thread fastening, a back gage and channel guide for causing the fastening to be inserted through the upper and lip of the insole, means for releasing the work, and means for automatically stopping the machine at the completion of the predetermined cycle of operations.

10. A machine for inserting individual unconnected thread fasteners through the upper and insole lip of a lasted shoe having,

in combination, mechanism for forming a thread fastener in the upper and lip of the insole, a back gage and channel guide for clamping the upper and lip between them during the formation of the fastener, mechanism for actuating the positioning devices to release the work upon the completion of the fastener, and means for automatically stopping the machine at the completion of the cycle of operations.

11. A thread handling machine having, in combination, positioning devices for the work, a curved needle for passing a plurality of loops of thread through the work, and mechanism for varying the extent of the advancing movement of the needle to form loops of varying sizes upon the opposite side of the work.

12. A thread handling machine having, in combination, positioning devices for the work, a curved needle for passing two loops of thread successively through the work, mechanism for actuating the needle to increase the forward throw when passing the second loop through the work, and means for engaging the first loop and passing it through the second.

13. A thread handling machine having, in combination, positioning devices, a needle, mechanism for actuating the needle to pass two loops of thread successively through the work, a thread finger, mechanism for actuating the thread finger to engage the first loop and pass it through the second, and mechanism for pulling upon the supply thread from the first side to draw the second loop into the work and lock the stitch.

14. A thread handling machine having, in combination, positioning devices for clamping the work during the formation of a fastening, a needle for passing a loop of thread through the work, mechanism for feeding the needle while the work is clamped in position to pass a second loop of thread through the work, a thread finger for passing the first loop through the second, and means for automatically stopping the machine upon the completion of the fastening.

15. A machine for inserting individual unconnected thread fasteners through the upper and insole lip of a lasted shoe, having, in combination, a back gage and channel guide for causing a thread fastening to be inserted through the upper and lip of the insole, a needle arranged to clamp the short end of the thread in the work as it passes therethrough, mechanism for actuating the needle, cooperating means for forming a completed thread fastening, and thread cutting means for automatically severing the thread at the completion of the fastening.

16. A thread handling machine, having in combination, a needle, mechanism for actuating the needle to pass two loops of thread successively through the work, a thread finger

- ger, mechanism for actuating the thread finger to pass the first loop through the second and to next release the loop, and mechanism for pulling upon the supply thread from the opposite side of the work to draw the loops into the work and lock the stitch.
17. A thread handling machine having, in combination, a needle for passing a plurality of loops of thread successively through the work from the same side, means for clamping the work with the opposite side permanently positioned in a fixed relation to the throw of the needle, a thread finger for engaging with one loop of thread and passing it through another, and mechanism for imparting a constant length of pull to the supply thread to draw the thread lock a fixed distance into the work irrespective of the thickness of the work.
18. A thread handling machine, having in combination, a channel guide fixed in position and bearing against the inside of the lip of the insole, a back gage bearing against the work opposite the channel guide, means for yieldingly moving the back gage into an operative position, a needle for passing a plurality of loops of thread successively through the work, mechanism for imparting a forward throw to the needle having a fixed relation to the channel guide, mechanism for passing one loop of thread through the other, and means for pulling upon the supply end of the thread from the outside of the work to draw the encircled loop into the work a fixed distance.
19. A thread handling machine having, in combination, a channel guide, a back gage, mechanism for actuating the back gage to clamp the work between the two during the formation of a fastening, mechanism for forming a complete fastening, a thread cutter supported upon the back gage, and mechanism for automatically actuating the thread cutter at the completion of a fastening.
20. A thread handling machine having, in combination, a channel guide, a back gage having a slot therein through which the supply thread passes, mechanism for forming a complete thread fastening in the work, and a cutting device coöoperating with the back gage to shear the supply thread against the edge of the slot at the completion of the thread fastening.
21. A thread handling machine having, in combination, work positioning devices, a curved eye pointed needle, mechanism for imparting two advancing movements of varying length to the needle, a thread finger, and mechanism for actuating the thread finger to engage the loop formed by the shorter throw of the needle and pass it through the loop formed by the longer throw of the needle.
22. A thread handling machine, having, in combination, work positioning devices, a curved eye pointed needle, mechanism for imparting two advancing movements to the needle, a thread finger, and mechanism for actuating the thread finger in a rectilinear direction to engage the first loop formed by the needle and pass it through the second.
23. A thread handling machine comprising a curved eye pointed needle, mechanism for imparting two advancing movements of varying length to the needle and a feeding movement between the advancing movements, a thread finger, mechanism for actuating the thread finger to engage the loop formed by the shorter throw of the needle and pass it through the loop formed by the longer throw of the needle, and means for clamping the work in a fixed position during the formation of the thread fastener.

FRED N. LA CHAPELLE.

Witnesses:

BURTON W. CARY,
MAY A. HURLEY.

- ger, mechanism for actuating the thread finger to pass the first loop through the second and to next release the loop, and mechanism for pulling upon the supply thread 5 from the opposite side of the work to draw the loops into the work and lock the stitch.
17. A thread handling machine having, in combination, a needle for passing a plurality of loops of thread successively through the work from the same side, means for clamping the work with the opposite side permanently positioned in a fixed relation to the throw of the needle, a thread finger for engaging with one loop of thread and passing it through another, and mechanism for imparting a constant length of pull to the supply thread to draw the thread lock a fixed distance into the work irrespective of the thickness of the work.
18. A thread handling machine, having in combination, a channel guide fixed in position and bearing against the inside of the lip of the insole, a back gage bearing against the work opposite the channel guide, means 25 for yieldingly moving the back gage into an operative position, a needle for passing a plurality of loops of thread successively through the work, mechanism for imparting a forward throw to the needle having a fixed relation to the channel guide, mechanism for passing one loop of thread through the other, and means for pulling upon the supply end of the thread from the outside of the work 30 to draw the encircled loop into the work a fixed distance.
19. A thread handling machine having, in combination, a channel guide, a back gage, mechanism for actuating the back gage to clamp the work between the two during the 35 formation of a fastening, mechanism for forming a complete fastening, a thread cutter supported upon the back gage, and mechanism for automatically actuating the thread cutter at the completion of a fastening.
20. A thread handling machine having, 45 in combination, a channel guide, a back gage having a slot therein through which the supply thread passes, mechanism for forming a complete thread fastening in the work, and a cutting device coöperating with the back 50 gage to shear the supply thread against the edge of the slot at the completion of the thread fastening.
21. A thread handling machine having, in combination, work positioning devices, a 55 curved eye pointed needle, mechanism for imparting two advancing movements of varying length to the needle, a thread finger, and mechanism for actuating the thread finger to engage the loop formed by the shorter throw of the needle and pass it through the loop formed by the longer throw of the needle.
22. A thread handling machine, having, in combination, work positioning devices, a 65 curved eye pointed needle, mechanism for imparting two advancing movements to the needle, a thread finger, and mechanism for actuating the thread finger in a rectilinear direction to engage the first loop formed by 70 the needle and pass it through the second.
23. A thread handling machine comprising a curved eye pointed needle, mechanism for imparting two advancing movements of varying length to the needle and a feeding 75 movement between the advancing movements, a thread finger, mechanism for actuating the thread finger to engage the loop formed by the shorter throw of the needle and pass it through the loop formed by the longer throw of the needle, and means for clamping the work in a fixed position during the formation of the thread fastener.

It is hereby certified that in Letters Patent No. 1,185,108, granted May 30, 1916, upon the application of Fred N. La Chapelle, of Beverly, Massachusetts, for an improvement in "Thread-Handling Machines," errors appear in the printed specification requiring correction as follows: Page 5, line 113, for the word "tread" read *thread*; page 6, line 77, for the word "served" read *severed*; and that the said Letters Patent should be read with these corrections therein that the same may conform to the record of the case in the Patent Office.

Signed and sealed this 25th day of July, A. D., 1916.

[SEAL.]

F. W. H. CLAY,

Acting Commissioner of Patents.
